UNITED STATES PATENT OFFICE

170,843

AWNING OR SIMILAR ARTICLE

Charles S. White, Dearborn, Mich.

Application June 5, 1953, Serial No. 25,338

Term of patent 14 years

(Cl. D21—6)

To all whom it may concern:

Be it known that I, Charles S. White, a citizen of the United States of America, residing in the city of Dearborn, county of Wayne, State of Michigan, United States of America, have invented a new, original, and ornamental Design for an Awning or Similar Article, of which the following is a specification, reference being had to the accompanying drawing, forming part hereof, wherein:

Fig. 1 is a perspective view of an awning or similar article, showing my new design; and

Fig. 2 is an enlarged fragmentary perspective view thereof.

Alternate portions of the awning or similar article indicated a and b in Fig. 2 are of contrasting appearance. The broken line shown in Fig. 1 is for illustrative purposes only.

This application constitutes a continuation-in-part of my co-pending application Serial No. D. 19,213.

I claim:

The ornamental design for an awning or similar article, substantially as shown and described.

CHARLES S. WHITE.
